UNITED STATES PATENT OFFICE.

JONATHAN MOORE, OF BROOKLYN, NEW YORK, ASSIGNOR TO HIMSELF AND ABRAM HORTON, OF SAME PLACE.

DESIGN FOR THE RIM OF VASES, &c.

Specification forming part of Design No. 5,466, dated January 9, 1872.

Specification describing a Design for Casting for Borders of Vases and Fountains, invented by JONATHAN MOORE, of Brooklyn, in the county of Kings and State of New York.

The nature of my design is fully represented in the accompanying photographic illustration, to which reference is made. I propose that this design shall be known by the convenient name of frogs and leaf to distinguish it from analogous goods which I am manufacturing, showing other ornamental designs.

A represents a portion of the body of the casting, which may be variously curved, according to the size, depth, &c., of the vase or fountain, and may, at the point adjacent to and supporting the portion where my design is produced, be horizontal or vertical, or inclined to various degrees. I prefer that it be gracefully curled over so as to present the decorated portion in the inclined position. B B are leaves partially superposed upon other leaves C of a similar general design. D D D are flowers and partially-opened buds, standing, as represented, among the leaves, as shown. E are frogs figured in the natural crouching position, each resting upon one of the leaves C.

What I claim as my invention is—

A design for vases and fountains, in which the border or rim is composed, as shown, with frogs resting upon leaves, substantially in the manner described and set forth.

In testimony whereof I have set my name in presence of two subscribing witnesses.

Witnesses: JONATHAN MOORE.

ABRAM HORTON,
ARNOLD HOERMANN.
